UNITED STATES PATENT OFFICE.

FREDERICK G. SARGENT AND ALLAN C. SARGENT, OF GRANITEVILLE,
MASSACHUSETTS.

WOOL-WASHING MACHINE.

SPECIFICATION forming part of Letters Patent No. 293,789, dated February 19, 1884.

Application filed March 2, 1883. (No model.)

To all whom it may concern:

Be it known that we, FREDERICK G. SARGENT and ALLAN C. SARGENT, of Graniteville, in the county of Middlesex and State of Massachusetts, have invented a new and useful Improvement in Wool-Washing Machines, of which the following is a specification.

Our invention relates to wool-washing machines; and it consists in arranging two sets 10 of toothed bars, which alternately reciprocate and carry the wool forward through the bowl of the washing-machine, at an incline upward, through the length of the machine, so as to carry the wool from within the liquid of the 15 machine, and where it is fed in upward and forward, and for a considerable distance above the liquid before it reaches the squeeze-rolls, these sets of toothed bars being the only means of so conveying the wool out of the bowl and 20 through the space above the liquid to drain it; secondly, in providing above these toothed bars sprinkling-pipes, extending transversely across the bowl where the wool is being carried above the surface of the liquid, which has 25 the effect of rinsing and cleansing the wool with fresh liquid while passing through the air to the squeeze-rolls; thirdly, in providing a feeding-roller for feeding the wool into the bowl, which doffs the wool from it and prevents its adhesion to its surface by means of 30 liquid forced through perforations in its shell; and, fourthly, in providing a doffer-roller for the lower squeeze-roll which doffs the wool from the surface of that roll, and has the wool 35 thrown off from its surface by means of perforations in its shell, through which liquid is forced for that purpose.

Heretofore two sets of reciprocating bars have been used to convey wool through the 40 bowl of the wool-washing machine to the squeeze-rolls, said bars being provided with teeth and reciprocating alternately; but such bars were not placed at an incline extending from the bottom of the bowl at its feed-in end 45 to the top of the chute at the squeeze-roll end, and so as to convey the wool for a considerable distance through the air above the liquid before reaching the squeeze-rolls. We place these bars in this position, and to increase the 50 efficiency of the bowl we provide sprinklers

for saturating the wool with fresh washing-liquid where it passes through the air, thus enabling the wool to be passed under the washing process of two or more qualities of washing-liquid in the same bowl.

Heretofore it has been necessary to pass the wool through successive bowls of the machine to accomplish this, the heavier and greasier liquid being in the first bowl, another quality of liquid in the second bowl, and so on; but by our invention we reduce the number of bowls necessary to be used in the practical operation of the machine. We also provide a feeding-roll for conducting the wool into the machine, and a doffer-roll for conducting it away from the squeeze-rolls into the next bowl, so constructed as to have perforations in their shells, through which liquid is forced from a pump while they are in revolution, and the wool thrown from their surfaces as well as 70 forcibly saturated with the washing-liquid, which is thus caused to penetrate more thoroughly through the fibers and open up and cleanse them better.

In the drawings, Figure 1 is a top plan view 75 of the machine, with a part of the reciprocating bars and perforated bottom underneath broken away to show the construction of parts. Fig. 2 is a longitudinal vertical section through the machine, showing the operation of the 80 several parts.

A is the bowl of the machine, constructed in the usual manner.

B B' are the squeeze-rolls, arranged so as to be almost entirely above the surface of the 85 liquid in the bowl.

H is a force-pump attached to the side of the machine, and driven by a shaft, h, and pulley h'. This pump is used not only to draw away the contents of the bowl in cleansing it through the perforated pipes a', extending across the bottom of the bowl, but also, when the washing of the wool is going on, to force liquid through other pipes, for assisting in the operation, substantially as hereinafter 95 described.

In the bowl of the machine, and inclining upward from the end where the wool is fed in, is placed a perforated removable bottom or incline, D, provided with perforations d, for 100

the escape of the liquid through it, and a larger perforation, d^2 , to operate the reciprocating toothed bars through. This inclined bottom D serves to prevent the fiber from being washed down between the bars by the force of the washing-liquid from the pipes a^2 above falling upon them, as hereinafter described. e^2 are two sets of toothed bars, running longitudinally the whole length of the bottom D, all the bars covering it for the entire breadth of the machine. These bars e^2 have cracks or joints between them sufficient to allow the washing-liquid to escape down through them and the perforated bottom D underneath. All the bars e are attached together, and all the bars e^2 are attached together, and one set, e , is made to reciprocate in one direction by the pitman e^1 , while the set e^2 is made to reciprocate in the opposite direction by the pitman e^1 , the pitmen e^1 and e^2 being driven by the oppositely-placed eccentrics on the shaft G, which is in turn driven by the pulley g.

e is a feed-roll for feeding or conveying the wool into the machine, and is composed of a perforated shell, as shown, mounted upon a shaft, C, driven by pulley c^1 . The shaft C is hollow and perforated, and leads through bearings into the pipe c^2 in such a manner that liquid forced through this pipe will pass through the shaft and its perforations, and out through the shell of the roll e , and striking with force against the wool will not only saturate its fibers thoroughly, but throw it off from the roll, and while doffing the roll materially aid in the washing process.

F is a curved apron or chute, to conduct the wool from the feed-roll e upon the reciprocating bars e^2 .

N is a doffer-roller, constructed in all respects similar to the roller e , and, combined with its shaft n and pipe n^2 , leading to the pump H in substantially the same manner. It serves to doff the wool from the lower squeeze-roll, B, and to saturate it with a cleansing-liquid, which finally rinses it as it passes from the machine. It revolves in the same direction as the lower squeeze-roll, and is driven by a cord leading around its shaft or axis, as indicated in dotted lines in Fig. 2.

a^2 are pipes leading across the bowl over the part of the reciprocating bars e^2 which is above the surface of the liquid in the bowl A. These pipes are perforated on their lower sides, and are connected by the pipe a^2 with the force-pump. Liquid forced through them falls upon the wool above the liquid in the bowl, and serves to wash and rinse the latter thoroughly before reaching the squeeze-rolls.

60 The pipes a^2 are connected to the pump by the pipe a^3 , and a valve, a^4 , is provided to shut them off and open the pipe a^2 when desired.

By first washing the wool in the greasier and dirtier liquid in the bowl A, and then 65 forcing through it a clean, liquid from the

pipes a and doffer-roll N, after it has left the liquid in the bowl A, we are enabled to greatly increase the capacity of the bowl. In explanation of this it should be stated that it is customary to use a greasier, dirtier, and heavier liquid for washing in the first bowl, a different one in the second, not so greasy or dirty, and still different ones in the third and fourth bowls; and when the liquid in the first bowl becomes too much impregnated with grease and dirt it is drawn off and replaced by the liquid of the second bowl, and the second by that of the third, and so on, fresh liquid being placed in the last bowl of the machine, through which the wool passes. By this means the washing-liquid is utilized to its full capacity, and the wool, when finally coming from the machine, passes last through the clean washing-liquid.

By using a cleaner washing-liquid for forcing through the pipes a^2 and doffer-roll N, we are enabled to subject the wool to the effect of two liquids in one bowl, and by allowing cleaner liquid to drain from the wool into the bowl we can draw off the dirtier and heavier parts of the liquid, by the use of the pump, through the pipes a^2 , and we are thus enabled to keep the liquid in the bowl A more nearly of an even quality, while increasing the washing capacity of the bowl.

What we claim as new and of our invention is—

1. In combination with the bowl A, the perforated feed-roll e , connected with the pipe c^2 , and arranged on the bowl, substantially as described.

2. The perforated doffer-roll N, connected with the pipe n^2 , in combination with the squeeze-rolls B B', substantially as described.

3. In combination with the bowl A, squeeze-rolls B B', and bottom D, the alternately-reciprocating sets of bars e^2 , extending from the bottom of the bowl at the feed-in end entirely below the surface of the liquid to said said squeeze-rolls above the surface of the liquid at the delivery end, and upon an incline partly below and partly above the surface of the liquid in the bowl, and adapted to convey the fiber from the feed-in end to the delivery end of the bowl upon said bars, substantially as described.

4. In combination with the bowl A, the bars e^2 , extending partly below and partly above the surface of the liquid in the bowl, and adapted to convey the fiber thereon through the same, one or more perforated pipes, a , extending over the portion of the carrier above the liquid in the bowl, substantially as described.
